TYPE-WRITING MACHINE

1,101,108.

Specification of Letters Patent. Patented June 23, 1914.

Original application filed August 22, 1910, Serial No. 578,457. Divided and this application filed May 4, 1911. Serial No. 824,919.

To all whom it may concern:

Be it known that I, CHARLES H. VOGEL, a subject of the King of England, residing in Vancouver, in the county of Vancouver, Province of British Columbia, Dominion of Canada, have invented certain new and useful Improvements in Type-Writing Machines, of which the following is a specification.

10 This invention relates to the line-spacing mechanism of typewriting machines.

This application is a division of my pending application No. 578,457, filed August 22, 1910.

15 A principal object of this invention is to provide simple and efficient means for intermittently rotating the platen; also to provide improved means for regulating the line-spacing movement of the platen.

20 A further object is to arrange the line-spacing mechanism so that it can be readily disconnected from the platen and held in an inoperative position when desired, to permit free rotation of the platen in either 25 direction.

I provide a pneumatic cylinder on the carriage, actuating a rod or rack which rotates the line-space wheel and platen. An adjustable stop regulates the movement of 30 the platen. The pneumatic cylinder is swiveled so that the rod can be swung out of engagement with the line-space wheel to permit free rotation of the platen. Means are provided for holding the mechanism 35 connected to or disconnected from the line-space wheel.

In the accompanying drawings, Figure 1 is a diagrammatic view of my invention showing the pneumatic cylinder in longitudinal section. Fig. 2 is a plan illustrating a sliding stop for regulating the degree of movement of the platen. Fig. 3 is a perspective of the stop.

By means of a key A, a stem B is depressed 45 through pin and slot connection b, so as to open a valve C, and admit air through a flexible hose D from a supply pipe E. This air flows through nipple 20 to which the hose D is attached, into a cylinder 30, forcing a preferably hollow piston 32 outwardly, so that the inclined teeth 33 of the rack 33 rotate a line-space ratchet wheel 35, which is carried by a platen 58, and rigid on axle 36. When a compressible fluid, like

air, is used, the hollow space in the piston 55 furnishes a large clearance chamber 50 in which the fluid can expand and contract; and this serves to cushion the piston both against sudden starting and against sudden arrest, thus reducing any tendency to overthrow the platen by violent operation of the line-spacing mechanism. In the Fig. 2 position, the rack 33 advances into a notch 40 in the corner of a stop 39, and is arrested by the face 40^a, that is, the bottom of the 60 notch. This gives a two-tooth movement of the rack and ratchet wheel. The block 39 may be slid by means of handle 44, in a transverse groove 38 in the carriage frame 1, to withdraw it completely from the path 70 of the end of the rack 33, and this will permit a three-tooth movement of the ratchet wheel, which is the maximum movement; or the block 39 may be pushed forward to present its full width in the path 75 of the rack, and the ratchet will then have a movement through only one tooth-space. A spring 42, having a detent 41 co-operating with recesses 43 in the face of the stop, enables the stop to be held in any one of 80 the three positions described. When the key A is released, it is raised by its return spring F, and the air in the cylinder exhausts at port G of the valve. The piston 32 is returned by a spring 49 in the chamber 85 50 attached to the cylinder head 54. As the rack slides back over the ratchet, there will be a slight upward movement or vibration of the rack and cylinder, which is permitted by a pivot screw 31 passing through 90 a plate 46, which is fixed to the cylinder, the said pivot screw being mounted in the carriage frame 1. A spring 47 presses against the points of a notch 48 in the edge of the plate 46, and tends to hold the cylinder with the rack 33 engaging the ratchet wheel, as shown in Fig. 1; and this arrangement permits the slight vibration of 95 the rack referred to above. The cylinder the rack may be swung up around the 100 pivot 31, to an elevated idle position where it will be held by the spring 47 co-operating with a notch 45, similar to the notch 48. The piston 32 is prevented from coming completely out of the cylinder by a screw 105 51 on an arm 52 on the forward end of the cylinder. This screw is put in place after the piston is inserted, and it should

be understood that this stop is far enough from the normal position of the piston to permit the rack 33 to advance through its three-tooth line-space movement.

5 Having thus described my invention, I claim:

1. A typewriting machine having a platen and a ratchet wheel for rotating the same, in combination with a pneumatic cylinder and piston, a rack carried by said piston and engaging said ratchet wheel, and adjustable means for limiting the extent of movement of said rack.

2. A typewriting machine having a platen and a line-space wheel, a rod engaging said wheel, a pneumatic cylinder, a piston in said cylinder connected with said rod for advancing said rod to rotate said wheel, said piston provided with a large clearance chamber for the purpose set forth, and movable stop in the path of said rod adapted to be held in different positions permitting a different degree of movement of said rod.

3. A typewriting machine having a platen and a line-space wheel, a rod engaging said line-space wheel, a stop mounted to slide transversely to the end of said rod, and means for holding said stop in different positions, said stop having a form permitting 30 a different amount of movement of said rod in the different positions of said stop.

4. A typewriting machine having a platen, a line-space wheel therefor, a rod engaging said line-space wheel to rotate the same, means for advancing said rod to effect the line-space movement, a block movable transversely in the path of the end of said rod and having a notch therein which may be held in alignment with said rod, 40 means for holding said stop with its full width in the path of said rod to effect a more limited movement of said rod, and means for holding said stop completely withdrawn from the path of movement of said rod to permit the maximum movement thereof.

5. A typewriting machine having a platen and a line-space wheel for rotating the same, in combination with a pneumatic cylinder, a piston and a rod connected to the piston and engaging said line-space wheel for rotating the same, said cylinder having a pivot permitting said rod to be swung out of engagement with said line-space wheel.

55 6. A typewriting machine having a platen and a line-space wheel, in combination with a pneumatic cylinder having an axis of rotation, a piston, and a rod connected to the piston to rotate said line-space wheel, and 60 means for holding said cylinder with said rod disengaged from said line-space wheel.

7. A typewriting machine having in combination a platen, a line-space wheel, a pivoted pneumatic cylinder, a piston, a rod connected to the piston and engaging said

line-space wheel to rotate the same, and a spring coöperating with said cylinder when rotated upon its pivot for holding said cylinder with said rod disengaged from said line-space wheel.

70

8. In a typewriting machine, the combination with a platen and a line-space wheel, of a pneumatic cylinder, a piston in said cylinder for driving said line-space wheel, a stop for arresting said piston to limit the line-spacing movement, a pivot on which said cylinder may swing to cause the piston rod to clear said line-space wheel, a detent holding said cylinder in said cleared position, and a stop for limiting the movement of 80 said piston when free of said line-space wheel.

75

9. In a typewriting machine, a line-space mechanism having means for connection with a source of pneumatic power for operating said mechanism, a cylinder forming part of said mechanism, a piston, a pivot on which said cylinder swings, and a spring for holding the cylinder in normal position.

85

10. In a typewriting machine, the combination with a line-space wheel, of a rod for driving said wheel, a plurality of teeth on said rod for engaging said wheel, a piston connected to said rod, and a swinging cylinder containing said piston.

95

11. In a typewriting machine, the combination with a platen, of mechanism for rotating the platen comprising a cylinder adapted to be connected with a source of pneumatic power, a piston, and a piston rod, 100 a pivot on which said cylinder swings, and a spring for yieldingly holding the cylinder either in or out of operative position.

100

12. In a typewriting machine, the combination with a rotary platen and a toothed line-space wheel, of a cylinder, a piston working therein, a piston rod tangential to the line-space wheel and provided with a tooth or teeth to engage the teeth of said wheel and drive the platen; said cylinder 110 pivotally mounted to permit the piston rod to be swung either into or out of position to coöperate with said wheel, and means to hold the cylinder in either of said positions.

105

13. In a typewriting machine, the combination with a rotary platen and a toothed line-space wheel, of a cylinder, a piston working therein, a piston rod tangential to the line-space wheel and provided with a tooth or teeth to engage the teeth of said 115 wheel and drive the platen, and an adjustable stop extending into the path of the free end of the piston rod to variably limit the throw of said rod.

115

14. In a typewriting machine having a 120 platen and a line-space wheel therefor having a rack, a pneumatic cylinder, a piston therein, a rod extending from said piston toward said wheel and having a fixed tooth in engagement with said rack to operate said 130

130

line-space wheel upon and by the application of pneumatic pressure to said piston, the capacity of said cylinder being sufficient to impart a cushioning influence to the operative stroke given said rod by said piston, a spring to return said rod at the completion of its operative stroke, and means enabling said rod to free its tooth from said rack on the return stroke.

10 15. A typewriting machine having a platen and a line-space wheel therefor, in

combination with a rod having means engaging said wheel to rotate it in line-spacing pneumatic means to operate said rod, means whereby said rod may be moved into 15 and out of operative position, and a spring to hold said rod in the position to which moved.
